UNITED STATES PATENT OFFICE.

DOROTHY V. D. WHITAKER, OF PHILADELPHIA, PENNSYLVANIA.

SLEEVE-PROTECTOR.

1,344,011.

Specification of Letters Patent. Patented June 22, 1920.

Application filed June 30, 1919. Serial No. 307,569.

To all whom it may concern:

Be it known that I, (Miss) DOROTHY V. D. WHITAKER, a citizen of the United States, and a resident of Philadelphia, in the county 5 of Philadelphia and State of Pennsylvania, have invented new and useful Improvements in Sleeve-Protectors, of which the following is a specification.

This invention relates to sleeve protectors 10 and advertising novelties and has particular references to that class of sleeve protectors adapted to be used to advantage by stenographers, typists, clerks, nurses, sales ladies, school girls and others to prevent the 15 wearer's sleeve from becoming soiled.

Heretofore sleeve protectors of the same class to which my invention pertains have been held or retained in position upon the wearer's sleeve by means of strings, elastic 20 bands, tabs or other equivalent means, all of which have been found defective in certain particulars and expensive to manufacture.

A primary object of the invention is to provide in a sleeve protector a simple and inexpensive means for retaining the sleeve 25 protector in position upon the wearer's sleeve, the means being of such a character as to permit the article to be manufactured at a relatively low cost as compared with 30 other similar articles of manufacture which are at present on the market.

A further object of the invention is to provide a sleeve protector of the above mentioned character so shaped as to permit a 35 maximum number to be placed for shipment in the smallest possible container or receptacle.

A further object of the invention is to provide a simple and effective means for 40 preventing the sleeve protector from cutting or chafing the wrist of the wearer.

A further object of the invention is to provide a sleeve protector which may be utilized for displaying certain advertising 45 matter and on which notes or memorandums may be kept at all times in view of the wearer.

Other objects and advantages of the invention will be apparent during the course 50 of the following description taken in connection with the accompanying drawings.

In the drawings, forming a part of this specification and wherein like numerals are employed to designate like parts throughout 55 the same,

Figure 1 shows a square piece of perfo-

rated paper which may be torn or separated along the line of perforation into a pair of sleeve protectors embodying my invention,

Fig. 2 shows a sleeve protector embodying 60 my invention applied to the sleeve of a wearer, and,

Fig. 3 shows the article embodying my invention detached.

In the drawings, wherein for the purpose 65 of illustration is shown a preferred form of my invention, the numeral 5 indicates as a whole a blank, preferably cut square as shown, perforated diagonally as shown at 6, the perforations making possible the easy 70

separation of the blank to provide a pair of sleeve protectors. One corner of the blank is coated with a suitable solution as shown at 7 which when moistened makes possible 75

the adhesion of one corner of the sleeve protector to the main body thereof as shown in Fig. 3. By applying the gum or adhesive to the corner of the blank it is apparent that only one operation is necessary to coat a 80 corner of each sleeve protector. It is fur-

ther apparent that by perforating the blank as shown at 6 a simple container adapted to receive a quantity of sleeve protectors in a relatively compact form may be employed. In actual practice it may be found desir- 85

able by a firm, should they desire to distribute these articles as an advertising medium, to print on one of the sleeve protectors a desired advertisement as expressed by the phrase "Use X Y Z cold cream." It 90

may be found desirable for the convenience of the wearer to leave the opposite corner of the sheet 5 blank so that any desired 95 memorandum may be written thereon which will be constantly in view of the wearer. A memorandum, for example, is expressed in the sentence "John Doe will call at 10 A. M. to see R. Roe" which is shown in Fig.

2. It will be noted that because of the peculiar shape of the sleeve protector the blank 100 portion adapted to receive the memorandum and likewise the portion having the advertising matter thereon will necessarily assume the position shown in Fig. 2 in which position either the memorandum or advertising matter is constantly called to the attention of the wearer.

In actual practice it has been found that when the blank 5 is cut or sheared rather than perforated as shown at 6 a sharp edge 110 necessarily results therefrom and this edge has been found to chafe or irritate the wrist

of the wearer but on the other hand when the blank is perforated so that it may be separated to form the sleeve protectors the small prickles as shown at 8 prevent chafing or irritation of the wrist and further serve as a reinforcement for the edge of the sleeve protector, thereby preventing it from becoming easily torn.

It is to be understood that the form of my invention therewith shown and described is to be taken as a preferred example of the same, and that various changes in the shape, size and arrangement of parts may be resorted to without departing from the spirit of the invention or the scope of the subjoined claims.

Having thus described my invention, what I claim as new and desire to secure and protect by Letters Patent of the United States, is:

1. A sleeve protector comprising a triangular piece of paper adapted to encircle the wearer's arm, said triangular piece of paper being provided with an irregular edge to prevent chafing of the wearer's wrist.

2. A sleeve protector comprising a triangular piece of paper adapted to encircle the wearer's arm, said triangular piece of paper being provided with an irregular edge

to prevent chafing of the wearer's wrist, and means for retaining the triangular piece of paper in an encircling position upon the wearer's arm.

3. A sleeve protector comprising a triangular piece of paper adapted to encircle the wearer's arm, said triangular piece of paper being provided with an irregular edge to prevent chafing of the wearer's wrist, and adhesive material carried at one corner of said triangular shaped piece of paper for securing the sleeve protector in an encircling position upon the wearer's arm.

4. The method of forming a pair of sleeve protectors from a single square sheet of paper which consists in diagonally perforating said sheet of paper and applying an adhesive to one corner of said square sheet of paper and separating said sheet along the diagonal perforation.

5. The method of forming a pair of sleeve protectors from a single square sheet of paper which consists in diagonally perforating said sheet of paper and coating the same with a suitable adhesive equal areas of each half of said sheet of paper at a corner thereof and separating said sheet along the diagonal perforation.

DOROTHY V. D. WHITAKER.
